UNITED STATES PATENT OFFICE.

DAVID W. GOULD, OF WASHINGTON, DISTRICT OF COLUMBIA, ASSIGNOR
TO CHARLES W. HAYES AND ALBERT A. FRIEDRICH, OF SAME PLACE.

OIL-CLEANSING APPARATUS.

SPECIFICATION forming part of Letters Patent No. 553,710, dated January 28, 1896.

Application filed April 3, 1895. Serial No. 544,290. (No model.)

To all whom it may concern:

Be it known that I, DAVID W. GOULD, a citizen of the United States, residing at Washington, in the District of Columbia, have invented certain new and useful Improvements in Oil-Cleansing Apparatus, of which the following is a specification, reference being had therein to the accompanying drawings.

My invention relates to an oil-cleansing apparatus; and it has for its object the production of a cleansing device that will effectively remove from the oil rendered impure by use the foreign substances, thus leaving the oil pure and clean, ready to be again utilized.

The invention will first be described in connection with the accompanying drawings, and then pointed out in the claims.

Figure 1 is a perspective view of my improved oil-cleansing device. Fig. 2 is a vertical central sectional view of the same. Fig. 3 is a sectional view of the inner oil-receptacle. Fig. 4 is a horizontal sectional view of the apparatus, taken on the line *x x*, Fig. 2. Fig. 5 is a reduced vertical sectional view, taken on the line *y y*, Fig. 3, illustrating the manner in which the discharge-pipes converge.

Referring to the drawings, A is a vessel, preferably rectangular, as shown, provided 30 on its front side with ordinary gages 1 and 2 and on the side with a faucet 3. This vessel is provided with a cover B, having an opening 4 through which oil is poured into the cleanser.

C represents the inner oil-receptacle, all its parts being preferably formed integral. One wall, 5, of this receptacle extends nearly to the bottom of the vessel, while the other wall, 6, is much shorter. These walls are of a width 40 to just fit within the vessel and are provided at their upper ends with overhanging lips 7, adapted to engage the sides of the vessel and hold the receptacle removably in place, as shown in Fig. 2. To the wall 5, a short distance below its upper end, is secured a plate D, which inclines downward toward wall 6 and is secured thereto, this plate being of a width equal to the interior diameter of the vessel A. Near the wall 6 the plate D is provided with a 45 central opening 8, and in this opening is placed

a screen d. Below plate D, and secured at one end to wall 6, is what I term "a separating-plate" E. This plate is provided on its upper side with a number of projections e, and inclines in a direction opposite to the direction of plate D. Near the wall 5 the end of the plate E is secured to the upper end of a pipe 9, which at its upper end is the same width as the plate E, but decreases in size until at the lower or discharge end it is circular in form and narrow in cross-section. This pipe 9 extends to near the bottom of the vessel and is so constructed that wall 5 forms one wall of the pipe. A short distance from pipe 9 there is secured to the under side of plate E an auxiliary wall F, which extends to near the bottom of the vessel A, and equal in width to the interior diameter of the vessel, thus dividing the vessel into two chambers below the plate E. A pipe 10, similar to pipe 9, is secured to the wall F and is provided at its lower end with a valve 11, for a purpose hereinafter described. Between the walls 5 and F is placed a screen G for screening the impurities from the rising oil.

Water being placed in the chambers a and a', the operation of my cleanser is as follows: Oil rendered dirty from use is poured into the vessel through the opening 4 in the top or cover B. It drops onto plate D, where it will 50 find its way down the inclined plate and through the opening 8 and screen d, thus removing some of the impurities. After passing through the screen the oil drops onto the plate E, where the projections e serve to break 55 the oil into globules and also to remove some of the impurities. After leaving the plate E the oil passes down the pipe 9, from which it is discharged into the water in chamber a' through which it passes, rising upward 60 through screen G and accumulating on top of the water. When sufficient oil has accumulated to cause the surface to rise to the level of the inlet of pipe 10 it will flow into the pipe. As the lower end of this pipe is 65 protected with a valve no water can get in it, and the oil, when sufficient has accumulated to exert more pressure than the water, will force the valve open and flow out into chamber a, where it will gradually filter through 70

the water in that chamber and accumulate on its surface, where it may be drawn off through faucet 3 ready for use, the gages 1 and 2 serving to show the conditions of the oil and water.

5 The bottom of the vessel just below each chamber is curved downward and at the lowest point is provided with a discharge-pipe 12, permitting the impurities which fall to the bottom to be drawn off. Jet steam-pipes H 10 lead into each chamber, permitting the operator to keep the water at an even temperature and also to agitate it to more effectively remove impurities from the oil.

Though I have described water as the purifying-liquid it is evident that any other purifier could be used with equal facility.

By forming the inner oil-receptacle integral I am enabled to remove it from the vessel A and thoroughly clean it as occasion requires.

Having thus described my invention, what I claim as new, and desire to secure by Letters Patent, is—

1. In an oil-cleansing apparatus, a vessel, 25 and an inner oil-receptacle adapted to be placed in the vessel, said oil-receptacle comprising an upper chamber, a separating-plate below the chamber, a partition secured to the separating-plate, and dividing the vessel into 30 two vertical chambers, and means for convey-

ing the oil from the separating-plate through the two chambers in succession.

2. In an oil-cleansing apparatus, a vessel, and an integral inner oil-receptacle adapted to be placed in the vessel, said oil-receptacle comprising an upper chamber, a separating-plate below the chamber, a partition secured to the separating-plate and dividing the vessel into two vertical chambers, and means for causing the oil to pass through first one chamber and then through the other.

3. In an oil-cleansing apparatus, a vessel, and an inner oil-receptacle adapted to be placed in the vessel, said oil-receptacle comprising an upper chamber having an inclined bottom, an inclined separating-plate secured below the chamber, a partition secured to the separating-plate and adapted to divide the vessel into two vertical chambers, a conveying-pipe secured to the separating-plate for conveying the oil through the first chamber, and a second pipe secured to the partition for conveying the oil through the second chamber, substantially as described.

In testimony whereof I affix my signature in presence of two witnesses.

DAVID W. GOULD.
